(57) **CLAIM**

The ornamental design for an assistive gripping device for intelligent device, as shown and described.

DESCRIPTION

FIG. 1 is a front perspective view of an assistive gripping device for intelligent device showing our new design;
FIG. 2 is a rear perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is an enlarged view of the portion indicated by line 9 in FIG. 2.

The dash-dash broken lines in the drawings depict the portions of the assistive gripping device for intelligent device which form no part of the claimed design.

The dot-dash broken lines of FIGS. 2 and 9 indicate where the enlargements have been taken, and form no part of the claimed design.
